(57) **CLAIM**

I claim the ornamental design for a planter, as shown and described.

DESCRIPTION

FIG. 1 is a front plan view of the planter showing my new design;

FIG. 2 is a rear plan view thereof;

FIG. 3 is a right side plan view thereof;

FIG. 4 is a left side plan view thereof;

FIG. 5 is a top plan view thereof;

FIG. 6 is a bottom view thereof; and,

FIG. 7 is a top perspective view thereof.

The broken lines in the drawings represent unclaimed environmental subject matter and form no part of the claim.
